His Attorney.

UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

REFRIGERATING MACHINE

Application filed June 10, 1931. Serial No. 543,406.

My invention relates to refrigerating machines, and more particularly machines of the type having a compressor enclosed in a casing containing a body of oil in the lower portion thereof to provide for lubricating the compressor.

It has been proposed to support machines of this type heretofore at the bottom of the casing. In such a construction heat has been conducted from the bottom of the casing to the supporting base, which resulted in cooling of the lubricating oil and condensation of refrigerant in the oil. This condensation of refrigerant in the oil impairs its lubricating qualities and makes the machine noisy in operation.

The object of my invention is to provide a simple construction for supporting a machine, and an arrangement such that the lubricant retains heat to such an extent as to prevent the condensation of refrigerant therein. I accomplish this by constructing the support in such manner that it is conductively isolated from the portion of the casing containing the body of lubricant to allow the body of lubricant to retain heat, and support the machine in an opening in a base so as to simplify the construction.

Further objects and advantages of my invention will become apparent as the following description proceeds, and the various features of novelty which characterize my invention are pointed out with particularity in the claims annexed to and forming a part of this specification. For a better understanding of my invention reference may be had to the following description taken in connection with the accompanying drawing in which Fig. 1 is an elevation view, partly broken away, of a refrigerating machine embodying my invention; Fig. 2 is a perspective view of certain parts of Fig. 1, and Fig. 3 is a sectional view of part of the construction shown in Fig. 1.

Referring to the drawing, I have shown my invention in connection with a compression refrigerating machine of the general construction shown in my United States Letters Patent No. 1,736,635 granted November 19, 1929. This machine comprises a compres-

sion casing 1 having a motor 2 and compressor 3 arranged therein which are supported in the casing on springs 4 and arranged above a body of lubricating oil 5 therein. The compressed refrigerant gas is discharged from the compressor 3 into the casing 1 and flows through a connection 6 into an air cooled condenser coil 7 which is arranged about an annulus of zig-zag heat dissipating elements or fins 8 secured to the casing 1, as described in my United States Letters Patents Nos. 1,797,029 and 1,797,030 granted March 17, 1931. In this construction the fins 8 are in good thermal contact with both the condenser coil 7 and casing 1 for effectively cooling the condenser coil and for dissipating the heat of the motor 2 and compressor 3 from within the casing. The refrigerant is condensed in the coil of pipe 7 and flows therefrom, under the control of a float valve 9, through a pipe 10 into an evaporator 11 supported by a hollow base 12 containing insulation 13 which is adapted to be removably supported in an opening of a refrigerating cabinet, and the vaporized refrigerant is withdrawn from the evaporator 11 by the compressor 3 through pipe 14 where it is compressed again and the refrigerating cycle repeated.

In accordance with my invention, I support the casing by the annulus of fins 8 formed, as indicated at 15, to entirely separate them from the portion of the casing in contact with the body of lubricating oil 5 and thereby reduce conduction of heat from the body of oil to the fins. The bottom of the casing 1 is conductively isolated from the walls of the hollow base 12 by clamping the bottoms of the fins 8 to an upwardly flared edge 16 of an opening in a top wall 17 of the hollow base, as indicated at 18, which avoids the conduction of heat from the bottom of the casing to the base. I prefer to secure the fins 8 to the edge 16 about the opening in the base by forming projections 19 at the lower ends of the fins which are bent about the edge 16 to secure the machine to the base, and secure a ring 20 between the projections and the flange 100 for retaining a gasket 21 about the flange.

This arrangement considerably simplifies the construction, as a massive base construction is not required.

Moisture is prevented from getting into the insulation 13 within the hollow base 12 by the insulating gasket 21 of low thermal conductivity, such as a hollow rubber tube, which forms substantially an air-tight seal between the upwardly flared edge 16 and the bottom of the casing 1. This gasket is retained in place by bending a downwardly extending portion 22 of the ring 20 about the gasket as shown in Figs. 1 and 3.

With this construction the portion of the fins 8 above the body of lubricating oil 5 cools the condenser coil 7 and dissipates the heat of the motor 2 within the casing whereas the portion of the fins entirely spaced from the part of the casing in contact with the lubricating oil only cools the condenser coil 7. In this manner the body of lubricating oil 5 retains heat to maintain it at a higher temperature than the condenser coil 7, and the compressed refrigerant gas will flow into the condenser coil and not condense in the lubricating oil. In addition the top wall 17 of the hollow base 12 cooperates with the fins 8 in dissipating heat to aid in the proper cooling of the machine.

Although I have shown my improved support in connection with a particular type of refrigerating machine, I do not wish to be limited to the particular arrangement set forth, and I intend in the appended claims to cover all modifications which do not depart from the spirit and scope of my invention.

What I claim as new and desire to secure by Letters Patent of the United States is:

1. A refrigerating machine including a compressor and an enclosing compression casing, said casing containing a body of lubricant to provide for lubricating the compressor, and means conductively isolated from the portion of said casing containing the body of lubricant for supporting said casing.

2. A refrigerating machine including a compressor and an enclosing compression casing, said casing containing a body of lubricant to provide for lubricating the compressor, and means in spaced relation to the entire portion of said casing in contact with the body of lubricant for supporting said casing.

3. A refrigerating machine including a compressor and an enclosing compression casing, said casing containing a body of lubricant to provide for lubricating the compressor, and means extending from the portion of the casing above the body of lubricant and entirely separated from the portion of said casing containing the body of lubricant for supporting said casing.

4. A refrigerating machine including a

compressor and an enclosing compression casing, said casing containing a body of lubricant to provide for lubricating the compressor, a condenser coil arranged about said casing and receiving refrigerant therefrom, and means conductively isolated from the portion of said casing containing the body of lubricant for supporting said casing.

5. A refrigerating machine including a compressor and an enclosing compression casing, said casing containing a body of lubricant to provide for lubricating the compressor, a condenser coil, and means including heat dissipating elements in heat exchange relation with said condenser coil and said casing and conductively isolated from the portion of said casing containing the body of lubricant for supporting said casing.

6. A refrigerating machine including a compressor and an enclosing compression casing, said casing containing a body of lubricant to provide for lubricating the compressor, a condenser coil, and means including heat dissipating elements secured in heat exchange relation with the portion of said casing above the body of lubricant and entirely separated from the portion of said casing containing the body of lubricant for supporting said casing, said heat dissipating elements having their outer ends in heat exchange relation with said condenser coil.

7. A refrigerating machine including a compressor and an enclosing compression casing, said casing containing a body of lubricant to provide for lubricating the compressor, a base having an opening therein, means in spaced relation to the entire portion of said casing containing the body of lubricant for supporting said casing in the opening in said base, and means between the edge of the opening in said base and said casing to form a seal.

8. A refrigerating machine including a compressor and an enclosing compression casing, said casing containing a body of lubricant to provide for lubricating the compressor, a base having an opening therein, means including heat dissipating elements in heat exchange relation with said condenser coil and said casing and in spaced relation to the entire portion of said casing in contact with the body of lubricant for supporting said casing in the opening in said base, and means including a material of low thermal conductivity between the edge of the opening in said base and said casing to form a seal.

9. A refrigerating machine including a compressor and an enclosing compression casing, said casing containing a body of lubricant to provide for lubricating the compressor, a condenser coil, a hollow base having an opening in the top wall thereof, means including a plurality of fins secured in heat exchange relation with said condenser coil.

- ser coil and the portion of said casing above
the body of lubricant and entirely separated
from the portion of said casing containing
the body of lubricant, the bottoms of said
5 fins being attached to the edge of the opening
in said base for supporting said casing,
and means including a material of low thermal
conductivity between the edge of the opening
in said base and said casing forming
10 a seal between said casing and said base.
10. A refrigerating machine including a
compressor and an enclosing casing, a condenser,
heat radiating members secured to
said casing, and a supporting base having
15 an opening therein, said casing being supported
by said heat radiating members on
the wall of said base about the opening there-
in.
11. A refrigerating machine including a
20 motor and compressor unit, a casing enclosing
said motor and compressor, a plurality
of fins secured to said casing, a condenser
arranged in heat exchange relation with said
fins and communicating with said compres-
25 sor, and a base having an opening therein,
said fins being secured in the opening in said
base for supporting the machine.

In witness whereof, I have hereunto set
my hand.

30 CHRISTIAN STEENSTRUP.
